UNITED STATES PATENT OFFICE.

FREDERIC C. MANN, OF EAST BRIDGEWATER, MASSACHUSETTS, AND
HENRY SCHUMACHER, OF NAVASOTA, TEXAS.

OIL-PRESS MAT.

SPECIFICATION forming part of Letters Patent No. 276,846, dated May 1, 1883.

Application filed October 18, 1882. (No model.)

To all whom it may concern:

Be it known that we, FREDERIC C. MANN, of East Bridgewater, in the county of Plymouth and State of Massachusetts, and HENRY SCHUMACHER, of Navasota, in the county of Grimes and State of Texas, have invented certain Improvements in Oil-Press Mats, of which the following is a specification.

This invention relates to mats between which cakes of ground cotton or other oil-yielding seed are held while being subjected to the action of the press which separates the oil from the cakes.

The invention has for its object to provide certain improvements in the construction of such mats, whereby they are made more efficient and durable than those in general use. To these ends our invention consists in the improvements which we will now proceed to describe and claim.

Of the accompanying drawings, forming a part of this specification, Figure 1 represents a top view of a mat embodying our improvements, a part of the upper sheet of leather being removed. Fig. 2 represents an edge view of the same. Fig. 3 represents a transverse section of the same on line $x x$, Fig. 1. Fig. 4 represents a view of a part of one of the leather sheets having a notched edge.

The same letters of reference indicate the same parts in all the figures.

In carrying out our invention we provide two rigid rectangular frames, A A, of suitable size, and composed of bars of iron strongly secured together. The space inclosed by each frame is covered by a sheet of wire-cloth, B, which is suitably secured to the frame. To the outer side of each sheet of wire-cloth we attach a sheet of leather, C, of such size as to cover the wire-cloth. The leather sheets are secured by detachable fastenings D, so that they can be removed for cleansing or renewal, said fastenings being preferably clips or staples of flexible metal passed through the wire-cloth and leather and bent over upon the outer surfaces of the latter. We prefer to interpose sheets of hair-cloth or other textile material, E, between the wire and the leather to prevent the wire from indenting the leather and mutually protect both the leather and wire.

The frames A A are connected by metallic links F F F' F', which are pivoted at their outer ends to a rod or handle, H, and at their inner ends, F³, to ears on the frames, the links F F being pivoted to the upper and the links F' F' to the lower frame. The links F F' have shoulders F⁴ F⁴, which abut against corresponding shoulders on the ears F³, and limit the extent to which said links can be opened or swung away from each other. Said shoulders are so formed that the links can only be opened sufficiently to permit the easy insertion of the oil-cakes between the leaves. The leaves are therefore kept abreast of each other—that is to say, neither can be moved longitudinally ahead of the other when the links are opened and the oil-cakes in place. The leaves are therefore obliged to move exactly alike when they are placed in the press-box, and each will exactly coincide with the other and reach the inner end of the press-box. This feature is very important, because if the leaves do not go back alike in the press-box the heavy pressure to which they are subjected will press them out sidewise and distort them, so that they will soon become useless.

The leaves of an oil-press mat have been before connected by links pivoted to the leaves and to a handle; but the links and the ears on the mats, to which the links are pivoted, have not been provided with shoulders, as ours are, the connection having been such that the leaves can move endwise independently of each other, and are therefore liable to be improperly placed in the press-box.

Two oil-cakes inclosed, as usual, in press cloths or bags may be placed between the frames A A. When pressure is applied the wire sheets, cloth sheets, and leather sheets combine to produce continuous channels for the escape of oil from all parts of the outer surfaces of the cakes, thereby greatly facilitating the yield of oil. The leather sheets, being somewhat yielding, prevent the powerful pressure employed from seriously injuring the press-cloths in which the cakes are inclosed, and obviate the liability of breaking the press, which exists when the mats are made of entirely rigid material. The cloth sheets interposed between the leather and wire make the mats more dura-

ble by equally protecting the leather and wire, as above stated, and also contribute to the elasticity of the mat. The rigid metal frames prevent the mat from stretching, so as to exceed the space allotted to it in the box of the press. The detachable connections of the leather sheets enable them to be readily removed when the mat becomes gummed and hard, so that the mat can be readily cleaned.

10. If desired, a middle leaf or sheet of leather or other suitable material may be used when two cakes are pressed in one mat, said leaf being interposed between the two cakes.

If desired, the leather sheets may be notched at their edges, and provided preferably with notched metallic re-enforcing strips N, as shown in Fig. 4. The notches afford means for the escape of oil in case the leather sheets become extended by use, so that they bear at 20 their edges against the sides of the press-boxes in which the mats are placed.

It will be observed that the numerous perforations of the wire-cloth sheets enable the fastenings D D to be passed through any desired parts of said sheets, so that as the leather sheets become laterally extended by constant pressure the points of enlargement of the fastenings D D with the wire-cloth may be changed from time to time to keep the leather in a 30 smooth condition without detriment to the wire-cloth.

We claim—

1. The improved oil-press mat composed of the rigid frames A A, sheets B B, of wire-cloth, secured to said frames, and outer sheets, C C, of leather, secured to the wire-cloth sheets, and the detachable fastenings D D, passed through the leather and the wire-cloth, the numerous perforations of the leather enabling said fastenings to be passed through different parts of

the wire-cloth without detriment to the leather, as set forth.

2. The improved oil-press mat composed of the rigid frames A A, sheets B B, of wire-cloth, secured to said frames, sheets E, of textile fabric, laid upon the outer surfaces of the sheets B B, and leather sheets C C, laid upon the outer surfaces of the cloth sheets, and secured in place by detachable fastenings D D, passing through the leather, cloth, and wire sheets, the 45 fabric sheets E protecting both the wire-cloth and the leather, while the leather and fabric sheets form a yielding backing, whereby the wire-cloth is prevented from injuring the press-cloths, and a somewhat yielding character is 50 imparted to the mat, as set forth.

3. In an oil-press mat, the leather sheets having notched edges, as set forth.

4. In an oil-press mat, the leather sheets having notched edges provided with metallic re- 60 enforcing strips, as set forth.

5. The leaves having ears F³, combined with the links F F', pivoted to said ears and to an operating-handle, said links and ears having shoulders whereby the separation of the leaves 65 is limited, and each is prevented from moving endwise independently of the other when the oil-cakes are in place, as set forth.

In testimony whereof we have hereunto signed our names each in the presence of two 70 subscribing witnesses.
